UPWARD ACTING DOOR CONSTRUCTION

Anthony Venditti, Detroit, Mich., assignor to
Crawford Door Company, Detroit, Mich., a corporation of Michigan

Application November 22, 1944, Serial No. 564,596

5 Claims. (Cl. 20—19)

1

This invention relates to upward acting closures which can be readily installed in buildings, garages and the like without the aid of experienced or skilled labor.

Specifically, the invention relates to an upward acting door assembly wherein the actual closing member or door is attached to door hardware, and wherein the door hardware is so prefabricated that a complete operating door assembly can be quickly installed in a doorway with the aid of only a hammer, a wrench, and a screw driver.

A feature of the door hardware is that it will operate as an upward acting assembly in a doorway without the closure member or door being attached to the hardware.

According to this invention, an inexpensive, efficient and easily installed upward acting tilting type door construction is provided for producing all of the advantages of an overhead door without the heretofore-encountered expense and installation difficulties.

The doors of this invention swing on links or arms from closed vertical position to open overhead horizontal position while the upper ends of the doors are supported on overhead horizontal tracks. The invention provides door assemblies which can compete favorably on a price basis with hinged doors, and can be installed by the average home-owner with less skill than is required for the installation of hinged doors.

Doors of this invention have end edges formed with pre-cut slots, grooves, holes or other retaining apertures, and can be provided in a plurality of individual door sections. Since the door is mounted on the hardware instead of the customary mounting of the hardware on the door, the door itself is not loaded, and is a mere filler or doorway closing means that can vary widely in construction. Cheap lightweight wood or sheet metal doors can be used, as well as heavy fancy doors.

The hardware in the door assemblies of this invention includes two linked-together assemblies composed of metal strips for attachment to the edge portions of the door, links pivoted to the metal strips, and bracket-carrying weatherstrips for attachment to the door jambs. The metal strips carry rollers which ride in tracks to guide the top end of the door. These strips also carry coil spring retaining brackets and link pivot brackets. Coil tension springs are provided, and each spring has one end secured on the metal strip carried spring retaining bracket, and the other end secured on a retainer adjacent the

2

pivot connection between the link and weather-strip.

In one form of the invention, the springs are pivotally arranged on double pivots relative to the metal strips, so that they will exert a straight upward pull on the door in closed position to prevent slamming, and an inward pull on the door in open position to hold it in open position.

In another form of the invention, the pivot arrangements between the link arms and metal strips are such that the pivot points are substantially vertically aligned with the pivot points of the spring-retaining brackets on the metal strips when the door is in closed position to prevent slamming of the door. However, these pivot points, in this other form of the invention, are shifted as the door moves to open position so as to be behind the spring retainer pivots thereby causing the springs to have an inward pull on the door for holding it in open position.

The metal strips extend along the entire height of the door and serve to secure the door sections together if a plurality of sections are used, in addition to serving as supports and rigidifying means for the door. These metal strips preferably take the form of channels or angles which embrace the side edges of the door and have tangs or inwardly projecting lugs for fitting in recesses in the side edges of the door. These tangs and recesses serve to automatically correctly position the channel or angle strip to the door.

The metal strips and weather strips of the link assemblies are preferably bolted together to facilitate installation.

To operatively assemble doors of this invention in a doorway, it is only necessary to carry out the following steps:

(1) The door is laid in a flat position adjacent the doorway on horses or the like supports, and the bolted together assemblies of metal strips, links and weatherstrips are secured to the door by nailing or securing the metal strips onto the side edges of the door. The tangs or lugs on the metal strips and the recesses in the side edges of the door will automatically correctly align the metal strips on the door.

(2) The door with the hardware secured thereon is tilted into the doorway and leveled, and the weatherstrips are attached to the door jambs of the doorway.

(3) The overhead tracks are mounted in position.

(4) The screws temporarily holding the metal strips and weatherstrips together are removed, and the door is swung to open overhead position, and

the coil springs are hooked onto the strip carried brackets and the pivot supports adjacent the pivots between the links and weatherstrips.

In one form of the invention the metal strip for attachment to the door is an angle strip with one leg extending over the side edge of the door while the other leg extends over the inner face of the door for only a part of the length of the strip and is then bent laterally outwardly from the door to overlie the weatherstrip on the door jamb. The laterally outward position of the leg extends along that upper portion of the door which tilts inwardly while the portion of the leg that overlies the inner face of the door extends along that lower portion of the door which tilts outwardly. The weatherstrip extends from the top to the bottom of the doorway, and has a portion projecting laterally into the doorway to overlie the leg of the angle strip on the inner face of the door, together with a bent portion overlying the side face of the door jamb so that the laterally extending leg portion of the angle strip will overlie the weatherstrip. In this arrangement the weatherstrip can carry a track supporting bracket, so that the correct position of the track is insured.

It is, then, an object of this invention to provide an inexpensive upward acting door construction that can be readily installed by the average home-owner without the aid of special tools.

A further object of the invention is to provide an upward acting door construction wherein the door becomes a mere doorway filler, and is attached to door supporting hardware.

A further object of the invention is to provide preassembled door hardware, and pre-cut doors for mounting on such hardware so that upward acting doors can be quickly installed by unskilled labor.

A further object of this invention is to provide a pre-cut door and pre-assembled linkages of door hardware which readily receive the door and are readily attached to door jambs for tiltably carrying the door.

A still further object of the invention is to provide pre-assembled door hardware for use with coil tension springs wherein the coil springs will automatically have a straight upward pull on the door in closed position to prevent slamming, and will have an inward pull on the door in open position to hold the door in open position.

A still further object of the invention is to materially reduce the manufacturing and installation costs of upward acting garage doors.

Other and further objects of the invention will be apparent to those skilled in the art from the following detailed description of the annexed sheets of drawings which, by way of preferred example only, illustrate one embodiment of the invention.

On the drawings:

Figure 1 is an elevational view of a doorway, viewed from the inside thereof, and having a door according to this invention mounted therein in closed position.

Figure 2 is a broken vertical cross-sectional view, with parts in elevation, taken along the line II-II of Figure 1 but illustrating the door in partially opened position in the doorway.

Figure 3 is an enlarged fragmentary horizontal cross-sectional view, with parts omitted, taken along the line III-III of Figure 1.

Figure 4 is a front elevational view of the assembly of Figure 3.

Figure 5 is an end elevational view of a linked-together door hardware assembly according to this invention.

Figure 6 is a front elevational view of a door according to this invention.

Figure 7 is an enlarged cross-sectional view, with parts in elevation, taken along the line VII-VII of Figure 2.

Figure 8 is an enlarged fragmentary vertical cross-sectional view taken along the line VIII-VIII of Figure 1.

Figure 9 is an enlarged end elevational view of the spring bracket on the hardware of this invention.

Figure 10 is a front elevational view of the bracket assembly shown in Figure 9.

Figure 20 is an isometric view of a door frame for completely surrounding the door according to the modified embodiment of the invention.

Figure 21 is a horizontal cross-sectional view taken through a door equipped with a modified arrangement of metal strip according to this invention.

Figure 22 is a view similar to Figure 1 but illustrating another modified metal strip arrangement on the door.

As shown on the drawings:

In Figures 1 and 2, the reference numeral 10 designates a door, composed of superimposed horizontally extending door sections, for opening and closing a doorway 11 defined by a top lintel 12, side door jambs 13, 13, and a floor F.

Overhead tracks 14, 14 project inwardly from the doorway 11 at levels adjacent the lintel 12. These tracks 14 have front end flanges 14a secured to the inner faces of the side door jambs 13 by means of square-headed screws 15. The tracks 14 also have flanges 14b at their rear ends as best shown in Figure 2, which are secured by

means of bolts 16 to brackets 17 depending from an overhead beam 18 carried by the building containing the doorway 11.

The tracks 14 have curved bottom flanges 14c and flat top flanges 14d overlying the curved flanges. The flanges support and retain rollers

75

19 having axles 20 retained in the curled top ends 21a of weatherstrips 21. The weatherstrips 21 have outer portions for overlying the inner faces of the door jambs 13 and inner portions overlying the inner face of the door 10.

Each weatherstrip 21 is welded to the inner flange 22a of a channel strip 22 embracing the side edges of the door. The channel strip 22 extends from the top to the bottom of the door and the weatherstrip 21 is welded to the upper portion only of the strip.

The lower portion of each channel strip 22 has a bracket 23 welded to the inner flange 22a thereof. The brackets 23 are pivotally connected to the lower ends of link arms 24 by means of rivet-like pivot pins 25. The upper ends of the link arms 24 are pivoted to brackets 26 by means of rivet-like pivot pins 27. The brackets 26 are riveted or welded onto elongated weatherstrips 28 which are secured to the inner faces of the door jambs 13 and extend downwardly from the lower ends of the weatherstrips 21 to the bottom of the door. Wood screws 29 secure the weatherstrips 28 to the door jambs.

The upper ends of the weatherstrips 28 have brackets 30 riveted or welded thereon. These brackets 30 project inwardly from the inner faces of the door jambs 13 and also project laterally into the doorway 11. Rocker members 31 are pivoted to the laterally inward end faces of the brackets 30 by means of pivot pins 32. Spring retainer members 33 are pivotally connected to the rockers 31 by means of pivot pins 34. Coil springs 35 have the upper end coils thereof wrapped around the retainers 33. The lower end coils of the springs 35 receive retainers 36 which are hooked onto integral hook portions 24a of the link arms 24.

The door is thus secured at its side edges in the channel strips 22 and the upper end of the door is suspended from the tracks 14 through the rollers 19, axles 20, and weatherstrips 21 welded on the channel strips 22. The lower end of the door is pivotally connected through the link arms 24 with weatherstrips 28 secured to the door jambs. The door is thereby mounted in the doorway for swinging movement from the closed vertical position shown in Figure 1 through the intermediate open position shown in Figure 2, to a fully opened overhead position lying horizontally parallel with the tracks 14. The link arms 24 will swing about their pivots 27 from downwardly extending position, shown in Figure 1, to upwardly extending position for holding the bottom end of the door adjacent the lintel 12. The double pivots 32 and 34 for the upper end of the spring are arranged so that the spring will have a straight upward pull on the door in closed vertical position to prevent slamming of the door into closed position and an inward pull on the door in overhead position to hold the door open.

In order to lock the door in closed position, flipper devices best shown in Figures 1, 3 and 4 are provided on the inner face of the door 10 adjacent the side edges thereof at levels beneath the pivotal axes 27 for the door. As shown in Figures 3 and 4, a plate 37 is welded on the inner flange 22a of the channel strip and projects therefrom over the door to be secured to the door 10 by means of screws or the like. The plate has an offset portion 37a overlying and welded to the flange 22a of the channel strip 22 and, to permit full seating of the flange 22a on the weatherstrip 28, the weatherstrip 28 has an off-

set localized portion 28a thereof receiving the forwardly projecting end 37a of the plate. The arrangement is such that the weatherstrip 28 will contact the flange 22a of the channel strip along its entire length except at the localized portion 28a thereof. This portion 28a thereof will contact the plate portion 37a.

Raised portions 37b are formed on the plate in spaced opposed aligned relationship to define 10 pivot supports for a flipper member 38. The flipper member 38 has an offset front end portion 38a for engaging the weatherstrip 28. Ears 38b are provided on the sides of the flipper in spaced 15 relation from the end 38a thereof and a coil spring 39 is anchored at one end to each ear 38b and at the other end to a tang 37c turned up from the edge of the plate 37. The springs 39 pull the flipper 38 to the dotted line position shown in Figure 3, in which position the flipper 20 will clear the inner edge of the weatherstrip 28. A slide bar 40 is slidably mounted through a slot in an upstanding flange 37d of the plate, and through an aligned slot in an upstanding ear 37e of the plate.

The bar 40 has an upturned end portion 40a for acting as a presser foot to slide over the flipper 38 and depress it into locked position as shown in Figure 3. As indicated by the dotted lines in Figure 3, the bar 40 rocks relative to the plate 37 as it is moved from flipper-releasing position shown in dotted lines to flipper-locking position shown in solid lines. This rocking action provides a wedge for securing the flipper in locked position.

35 The inner end of the bar 40 is offset as at 40b and the offset portion is apertured to receive an actuating rod 41. A cotter pin 42 retains the rod in the aperture of the offset portion 40b. The rod 41 extends along the inner face of the door as best shown in Figure 1, to an actuating bar 42 of a lock device 43 secured on the inner face of the door. The device 43 has a handle 43a which, when turned, draws the bar 42 inwardly to pull the rod 41 and effect a sliding of the bar 40 to a position so that the spring 39 will release the flipper 38 from locked position. A similar bar 42a actuates a similar rod 41a to the lock bar 40 of the other locking device.

The flippers 38, upon being forced to locking 50 position by the bars 40, serve to pull the door into a fully closed position in the event that the door has not been fully closed, since the offset portions 38a of the flippers will engage the weatherstrips 28 and draw the channel flanges 22a into tight engagement with the weatherstrips.

Each weatherstrip 28, as also shown in Figure 1, has an inwardly offset localized portion 28b beneath the portion 28a thereof to form a pocket for receiving the bracket 23 when the door is in closed position, so that the flange 22a of the channel strips will not be held in spaced relation from the weatherstrips by the thickness of this bracket.

As illustrated in Figure 2, the link arms 24 are bent to provide depressed portions 24b in alignment with the flipper plate 37 and actuating bar 40 when the door is in closed position, so that sufficient clearance will be obtained for the locking device.

As best shown in Figure 5, a complete assembly 70 of weatherstrip 21, channel strip 22, link arm 24, weatherstrip 28, and spring rocker 31 is provided. This assembly is duplicated for each side edge of the door shown in Figure 6. Screws S of the self-tapping type temporarily hold together the weatherstrip 28 and channel strip 22 of each

assembly so that each assembly can easily receive a side edge of the door lying flat on horses and so that the door with the assemblies thereon can easily be tilted into the doorway, leveled in the doorway, and have the weatherstrip 22 easily attached to the door jambs.

As shown in Figure 6, the door can be made in three separate panels 10a, 10b, and 10c. The side edges of each panel have a plurality of transverse slots 45 therein. The channel strip 22, as shown in Figure 5, has an inner flange 22a for overlying the inner face of the door, a side flange 22b for overlying the side edge of the door, and an outer flange 22c for overlying the outer face of the door. The side flange 22b has tangs 46 turned up therefrom to project between the flanges 22a and 22c. These tangs 46 are positioned to fit into the slots 45 as best shown in Figure 7. The flange 22b of the strip 22 also has screw holes 47 therethrough to receive mounting screws 48 as shown in Figure 7 for securing the channel strip to the door. The tangs 46 serve to locate and carry the weight of the door and the screws 48 need only be heavy enough to secure the strip firmly to the door. The channel strip extends from the top to the bottom of the door and will fixedly connect all three panels 10a, 10b, and 10c. Of course, the door could be in one piece, or more than three panels could be used, without departing from the invention.

The door, such as the central panel 10b thereof, can have mounting holes 49 pre-drilled therein for receiving portions of the lock 43 therethrough so that the locking device can be actuated with a key from the outside face of the door.

The door also has a groove 50 along its bottom edge, as shown in Figure 8, and this groove receives a wooden strip 51 having a flexible sheet of rubber, fabric, or the like 52 wrapped therearound and depending from the bottom of the door to engage the floor F and form a seal for the bottom of the door. Nails such as 53 are forced through the lower edge of the door, the wrapped-around portion of the sheet 52, and the wood strip 51 to securely anchor the sheet to the bottom of the door.

The link arm 24, as best shown in Figures 5 and 11, is an angle piece with a leg 24c receiving the pivot pins 25 and 27 and with a second leg 24d in angular relationship therewith. This leg 24d has an inwardly bent free end edge 24e as best shown in Figure 12, to better surround and engage the spring 35 as it is seated in the arm to dampen out vibrations of the spring.

A portion of the flange 24d is cut out into the shape of the hook 24a, and this portion is bent inwardly as shown in Figure 12 to underlie the spring 35 and engage the spring retainer 36.

As best shown in Figures 9 and 12, the bracket 30 has a flat side wall 30a which is secured to the weatherstrip 38. Top and bottom flanges 30b on this side wall 30a converge to a channel portion 30c with a laterally offset projection 30d. This projection 30d extends beyond the weatherstrip 28 as shown in Figure 10 and has a side wall receiving the pivot pin 32. The rocker 31 has a top flange 31a receiving an adjusting screw 54 in threaded relation therethrough. This adjusting screw is locked to the flange by means of a locking nut 55 on the screw. The screw 54 engages the top face of the offset portion 30d when the door is in closed position and serves to control the vertical alignment of the pivot 34 with the pivot 27 for the link arm when the door is in

closed position so that the spring will not slam the door into closed position. When the door is swung into open position the rocker 31 is rocked about the pivot 32 and moves the screw 54 off of the bracket 30. The pivot 31 then becomes the effective spring pivot. Pivot 31 is inwardly of the link pivot 27 and the spring thus has an inward pull on the door to hold it in open position.

10 The retainer 33 pivoted to the rocker 31 is in the form of a flat plate with notches 33a along each side edge thereof receiving several coils at the top end of the spring 35. The coil spring 35 is threaded on the retainer 33 for a desired distance to adjust tension of the spring for counter-balancing the weight of the door.

15 In the embodiment of the invention shown in Figures 13 to 19 inclusive, the door 60 is mounted in the doorway 11 defined by the top lintel 12, the side door jambs 13, and the bottom floor F. The door 60 is composed of two sections 60a and 60b. The door 60 is received at the side edges thereof by linked-together assemblies 61 which operatively mount the door in the doorway for tilting from a closed vertical position to an open overhead position. Each assembly 61 includes an angle strip 62, a link 63, and a weatherstrip 64. The angle strip 62, as best shown in Figure 19, has a leg 62a covering the side edge of the door 60 and extending from the top to the bottom of the door. A leg 62b of the angle strip 62 overlies the inner face of the door and extends to a laterally outturned leg portion 62c. The outturned portion 62c terminates at the top of the door. 20 The portion 62c is of a length determined by the tilting axis of the door and only extends along that portion of the door which tilts inwardly. Tangs, lugs or other projections (not shown) are provided on the leg 62a for fitting into recesses 25 of the door to locate and carry the weight of the door and to hold the door sections 60a and 60b together.

25 The weatherstrip 64 is a flat strip projecting into the doorway 11 from the bottom of the door to a level adjacent the part of the door that tilts inwardly. This projecting portion 64a, as shown in Figure 19, terminates adjacent the top end of the leg portion 62b of the angle piece 62 and overlies this leg portion of the angle strip. The weatherstrip 64 has a part of portion 64a thereof bent at right angles thereto to provide a leg 64b from the top of the portion 64a to the top end of the strip. This leg 64b covers the side face of the door jamb 13 and is in opposed relation to the leg 62a of the angle strip, thereby forming a metal shoe against which the edge of the door can rub. This shoe protects the inner face of the door jamb. The leg 62c of the angle strip overlies the weatherstrip 64.

30 The two strips 62 and 64 therefore cooperate to provide weatherstrips for the sides of the door and to carry the door in the doorway. For assembly purposes, screws such as 8 temporarily connect the strips 62 and 64 against relative movement so that the door 60 can be laid flat on horses or other supports and the assemblies 61 can readily receive the door with the strips 62 of the assemblies being attached to the door. The door with the assemblies thereon is then tilted into the doorway, leveled in the doorway, and the strips 64 of the assemblies are secured to the door jambs by means of lag screws 65 or the like.

35 The weatherstrips 64, as best shown in Figures

13 and 17, have brackets 66 secured thereon at level beneath the legs 62c thereof. These brackets 66 have pivots 67 thereon, tiltably supporting spring retainers 60. These spring retainers have keyhole slots 68a in their upper ends adapted to receive the pivots 67 through the large ends thereof and the pivots have shanks 67a to receive the small ends of the slots whereby the retainers can be readily attached to the pivots. The retainers have notched ends receiving the end coils of counterbalancing tension springs 69. The opposite end coils of the tension springs 69 are threaded on notched ends of bottom retainers 70 which have keyhole slots 70a for receiving pivot pins 71 and for seating on the shanks 71a of these pivot pins. The pivot pins 71 are secured on brackets 72 carried by the lower ends of the link arms 63. These brackets 72 are pivotally connected by pivots 72 to lugs 74 on the weatherstrips 64 near the bottom ends of the weatherstrips. The brackets 72 thereby serve to pivotally connect the link arms 63 with the weatherstrips 64 and also pivotally carry the lower spring retainer 70 for the springs 69.

The upper ends of the link arms 63 have brackets 75 secured thereon similar to the brackets 72, and these brackets 75 are pivotally connected to brackets 76 on the weatherstrip 64 at levels beneath the brackets 66.

Each bracket 76 carries two horizontal pivot pins 77 and 78. The pivot pin 77, as shown in Figure 17, seats in a recess or notch 75a provided in the top edge of the bracket 75. The pivot pin 78 seats in an arcuate slot 75b of the bracket 75. The pins 77 and 78 serve to pivotally connect the link arms 63 with the weatherstrips 64 and, as explained above, the link arms in turn are pivoted to the angle strips on the door.

As shown in Figures 13 and 17, the angle strips 62 carry brackets 79 on the top ends of the legs 62c thereof and these brackets overlie the inner face of the door 60 and are also secured to the top of the door by means of lag screws 80. The brackets 79 carry rollers 81 which ride in tracks 82. The tracks 82 have their forward ends carried by brackets 83 on the upper ends of the weatherstrips 64. Thus the weatherstrips 64 are continued to the upper end of the doorway and serve to locate the correct position for the tracks 82 while the angle strips 62 carry the brackets for the rollers that ride in the tracks.

As best illustrated in Figures 14 and 17, when the door is in closed position the pivot 67 for the upper end of the spring 69 is substantially vertically aligned with the pivot 77 for the upper end of the link 63 and the spring has a substantially straight upward pull on the door 60. This prevents slamming of the door into closed position.

As shown in Figure 15, when the door is tilted in moving toward overhead open position, the slot 75b of the bracket 75 moves relative to the pivot 78, and the pivot 77 remains seated in the notch 75a to remain the effective pivot for the link arm.

As shown in Figure 16, when the bottom of the slot contacts the pivot 78, this pivot becomes the effective pivot for the link 63, and the notch 75a is moved out of engagement with the initial pivot 77. As a result of this shifting of pivots, the effective link arm pivot 78, when the door 60 is in open position, is forwardly of the spring pivot 67 and the spring 69 has an inward pull on the door to hold it in overhead open position. Therefore, instead of shifting pivots for the spring, the modified construction includes a shift-

ing of pivots for the link arm to produce a similar effect.

As also shown in Figures 14 to 16 the link arms 63 have side flanges 63a which are turned inwardly to a greater extent at the intermediate portions of the link arms than at the ends of the arms. As the spring 69 nests into a link arm 63, when the door approaches closed position, the flange 63a successively contacts more of the length of the spring 69 to dampen out vibrations of the spring, and, when the door is in closed position, contact between the spring and a portion of the flange 63a is insured.

The modified door construction of Figures 13 to 19 thus includes the assemblies 61 which position the tracks 82, carry the pivots for the springs and link arms, provide weatherstrips for the sides of the door, and receive the door for mounting it in a doorway. The temporary screws 85 securing together the weatherstrips and angle strips of the assemblies are easily removed when the door is mounted in a doorway so that the link arms can be effective to swingably support the door. The springs are easily mounted in position on their pivots 67 and 71 because the keyhole slots in the spring retainers 68 and 70 afford an easy method of connecting the springs.

If desired, as shown in Figure 20, a frame 85 can be provided to surround the entire door. This frame is conveniently composed of angle strips with legs 85a for overlying a face of the door and legs 85b at right angles thereto for covering the edges of the door. With this frame-type construction, the door can be composed of very inexpensive lightweight material. The door can readily be secured to either or both of the legs of the angle strips. The angle strips can be hinged or bolted together at the corners of the frame.

As shown in Figure 21, instead of having a leg of an angle strip extending over an edge of the door, an angle strip 86 can have a leg 86a secured to the inner face of the door by means of screws such as 87 and can have a leg 86b projecting inwardly from the inner face of the door to carry the brackets for providing assemblies similar to the assemblies 61.

As shown in Figure 22, the door 60 can receive a channel strip 88 on the inner face thereof and this channel strip can have side legs 88a bottomed on the door together with a connecting web portion 88b spaced inwardly from the inner face of the door. The inner face of the door can be slotted or grooved at intervals along its height as at 89, and tangs 88c can be stamped from the web 88b of the channel strip to fit in the grooves 89 so that the channel strip will locate and carry the weight of the door. Means such as bolts 90 can project through the web 88b of the channel strip to carry the brackets for forming assemblies similar to the assemblies 61.

All of the hardware parts for the doors of this invention can be formed by stamping operations on sheet metal. The strips for forming weatherstrips and angle strips can be made from the same strip stock throughout. Strip stock two and one-half inches wide and one-sixteenth inch thick is satisfactory for the average single garage door.

From the above descriptions it should be understood that the invention provides assemblies of hardware especially arranged for receiving doors. These doors are slotted or otherwise recessed so that they can be attached to the hardware only in the proper positions. The hardware

is inexpensively made from conventional metal strip stock and is furnished in such a manner that the doors can be quickly installed without special tools and by unskilled labor.

It will, of course, be understood that various details of construction may be varied through a wide range without departing from the principles of this invention, and it is, therefore, not the purpose to limit the patent granted hereon otherwise than necessitated by the scope of the appended claims.

I claim as my invention:

1. In an upward acting door construction, a pair of hardware assemblies each comprising a channel member having a roller adjacent one end thereof adapted to engage a trackway, a weatherstrip assembled to the jamb of a doorway, a link arm pivotally connected at one end to said weatherstrip and at the other end to said channel member adjacent the other end of said channel member, and a counterbalance spring connected to said weatherstrip and to said channel member, said pair of assemblies adapted to be aligned in parallel spaced relation and a door panel insertable between said assemblies and having opposite marginal portions received in firm assembly with said channel members.

2. In an upward acting door construction, a pair of hardware assemblies each comprising a channel member having a roller adjacent one end thereof adapted to engage a trackway, a weatherstrip assembled to the jamb of a doorway, a link arm pivotally connected at one end to said weatherstrip and at the other end to said channel member adjacent the other end of said channel member, and a counterbalance spring connected to said weatherstrip and to said channel member, said pair of assemblies adapted to be aligned in parallel spaced relation and a door panel insertable between said assemblies and having opposite marginal portions received in firm assembly with said channel members, said channel members and said door panel having interlocking tangs and recesses, and fastening means to secure said door panel to said channel members, whereby said tangs relieve said fastening means of support load.

3. In an upward acting door construction, a pair of hardware assemblies in spaced parallel alignment each comprising a channel member having a roller adjacent one end thereof adapted to engage a trackway, a weatherstrip assembled to the jamb of a doorway, a link arm pivotally connected at one end to said weatherstrip and at the other end to said channel member adjacent the other end of said channel member, and a counterbalance spring connected to said weatherstrip and to said channel member, and a plurality of vertically separated panel units insertable between said assemblies and received by each of said channel members in firm assembly.

4. In an upward acting door construction, a pair of hardware assemblies in spaced parallel alignment each comprising a channel member having a roller adjacent one end thereof adapted to engage a trackway, a weatherstrip assembled to the jamb of a doorway, a link arm pivotally connected at one end to said weatherstrip and at the other end to said channel member adjacent the other end of said channel member, and a counterbalance spring connected to said weatherstrip and to said channel member, and a plurality of vertically separated panel units insertable between said assemblies and received by each of said channel members in firm assembly, said channel members and said panel units each having interlocking mating means to engage one another for effecting load distribution between said panel units and said channel members.

5. In an upward acting door construction, a pair of hardware assemblies each comprising a channel member having a weatherstrip portion adjacent one end thereof, said weatherstrip portion having a roller adapted to engage a trackway journaled therein, a separate weatherstrip assembled to the jamb of a doorway, a link arm, a bracket adjacent the other end of said channel member pivotally connecting one end of said link arm to said channel member, a bracket carried by said separate weatherstrip pivotally connecting the other end of said link arm to said separate weatherstrip, said assemblies arranged in spaced apart parallel relation, a panel inserted between said assemblies having opposite marginal portions received by said channel members, said channel members each having inwardly directed tangs and said panel having recesses in the marginal portions thereof to receive said tangs and fastening means to secure said panel in firm assembly with each of said channel members, said tangs and recesses arranged to take the load off of said fastening means.

ANTHONY VENDITTY.
